Primary Examiner — Mehri F Bajoul*(74) Attorney, Agent, or Firm* — Womble Bond Dickinson (US) LLP(57) **CLAIM**

The ornamental design for a bowling assistive device, as shown and described.

DESCRIPTION

FIG. 1 is a top perspective view of a bowling assistive device in accordance with my design.

FIG. 2 is another top perspective view of the bowling assistive device in FIG. 1, with a bowling ball disposed on the ball cradle of the bowling assistive device.

FIG. 3 is a side view of the bowling assistive device shown in FIG. 1.

FIG. 4 is an opposite side view of the bowling assistive device shown in FIG. 1.

FIG. 5 is a bottom view of the bowling assistive device shown in FIG. 1.

FIG. 6 is a top view of the bowling assistive device shown in FIG. 1.

FIG. 7 is a front view of the bowling assistive device shown in FIG. 1; and,

FIG. 8 is a rear view of the bowling assistive device shown in FIG. 1.

The broken lines on the strap of the bowling assistive device in FIGS. 4, 6, and 8 depict seams and form part of the claim. The ball shown in broken lines, in FIG. 2, illustrates environmental structure and forms no part of the claim.
